UNITED STATES PATENT OFFICE.

FRANK J. SEABOLT, OF SCHENECTADY, NEW YORK, ASSIGNOR TO GENERAL ELECTRIC COMPANY, A CORPORATION OF NEW YORK.

MOTOR-CONTROLLING RHEOSTAT.

No. 852,851.

Specification of Letters Patent.

Patented May 7, 1907.

Application filed January 14, 1907. Serial No. 352,115.

To all whom it may concern:

Be it known that I, FRANK J. SEABOLT, a citizen of the United States, residing at Schenectady, county of Schenectady, State 5 of New York, have invented certain new and useful Improvements in Motor-Controlling Rheostats, of which the following is a specification.

This invention relates to devices for controlling electric motor circuits and has for its object the provision of a device of this character in which the starting and the speed regulation of the motor may be accomplished in a simple and efficient manner.

In carrying out my invention I provide in connection with the starting and speed regulating resistances, a single controlling arm adapted to control both of said resistances and thereby accomplish both the starting 10 and speed regulation. The contacts of the starting resistance are arranged in a row parallel with those of the regulating resistance and adjacent thereto, and the controlling arm or member is arranged to engage both rows of 15 contacts simultaneously. In order that the controlling member shall be effective to vary only one resistance at a time, I provide means whereby one resistance is short circuited while the other one is being varied. As the 20 member moves in one direction, as for instance during the starting movement, the regulating resistance is short circuited while during the speed regulating movement the starting resistance is short circuited. I also 25 provide means whereby upon the occurrence of abnormal circuit conditions the controlling arm is returned to the off or protective position with reference to the motor.

In the accompanying drawing in which I 30 have shown one embodiment of my invention, Figure 1 is a plan view of a starting and regulating rheostat embodying my improvements together with the proper circuit connections; and Fig. 2 is a detail of the operating mechanism.

Referring to the drawing, 1 is an insulating base of slate or soapstone provided with concentrically arranged resistance contact studs 2 and 3. The studs 2 form terminals of starting resistance 4 while the studs 3 are similarly connected to the regulating resistance 5. The resistance 4 is designed as a starting resistance to be connected in series with the

motor armature only while the motor is coming up to speed, whereas the resistance 5 is designed to be constantly in circuit if desired. 55 This resistance 5 is preferably arranged in the field circuit so as to regulate the speed of the motor by varying the field strength. The controlling member for these resistances 60 is an arm 6 pivoted at 7 and having its free end so arranged by means of brushes 6' and 7' as to engage studs 2 and 3 simultaneously, and is therefore adapted to control either one of said resistances as conditions may require. 65 The circuit connections of these resistances are such that, as the arm 6 is moved to the right, the starting resistance 4 will be gradually cut out of the armature circuit while when it is moved to the left the regulating 70 resistance 5 will be cut in.

In order that the regulating resistance 5 shall not be varied as the arm moves to start the motor, I provide means for short circuiting this resistance during the starting movement. This short-circuiting may be accomplished in various ways but I have found that a very convenient method of producing this result is to arrange a contact stud 8 and spring-pressed switch-arm 9 so that current 75 will pass directly to the field and short circuit the resistance 5. When the running position is reached, contact is broken between the contact 8 and switch 9 thereby opening the short circuit. An arm 10 is arranged to 80 be moved by the arm 6 as the latter moves to running position, and is provided with a brush 10' so that when it reaches the running position the brush 10' will make contact with stud 12. Stud 12 has electrical connection 85 with the last one of the studs 2 and is likewise electrically connected to a binding post which forms an armature terminal. The arm 10 being a conducting element, when it reaches the stud 12 current will pass through 90 the arm 10 to the stud 12 and thus short circuit the stud 2 and starting resistance 4. The arm 10 therefore has two functions. When it reaches the running position it breaks the short circuit on the resistance 5 95 and at the same time short circuits the starting resistance 4. The arm 6 may then be moved in a reverse direction and vary the resistance 5 without affecting the resistance 4. This particular arrangement of arm 10 100 for shifting the short circuit from one resist-

ance to the other has a further advantage in that the arm 10 may be used to return the arm 6 to the starting position. The arm 10 is provided with a spring 11 tending to return it to the off position. The two arms 6 and 10 are concentrically pivoted and move in the same plane so that the engaging edge 11' of the arm 10 causes the arm 6 to move the arm 10 in one direction and also causes the arm 10 to move the arm 6 in the opposite direction. The arm 10 is provided with an armature 13 adapted to engage the pole-pin of a no-voltage magnet 14 when the arm is on the stud 12. The magnet 14 thus maintains the short circuit of the starting resistance when sufficiently energized. When it releases and allows the arm 10 to return the latter carries with it the arm 6. I have shown the retaining magnet 14 connected across the line one terminal being grounded at the pivotal point of switch 9 although it is perfectly obvious that it may be otherwise connected if desired.

The operation of my device and the arrangement of circuits is as follows: Normally the device stands as shown in full lines in the drawing with the arm 6 held against the stop 15 by the arm 10 and spring 11. To start the motor arm 6 is moved by the handle 16 to the right gradually cutting out starting resistance, the current passing from the line at L, through the conductor 17 to center pivot 7 thence through arm 6, resistance 4, conductor 18, to armature A and back to line 35 at L'. At the same time field current passes from the pivot 7, through arm 10, to studs 2, thence through the starting resistance, conductor 19, switch 9, stud 8, through the field F and back to line. The field resistance 5 is thus short circuited as the arm 6 is moved to the right. When the running position is reached the arm 10 passes on to the stud 12 and is held there by the retaining magnet 14. The armature current now passes from the 45 pivot 7 directly to stud 12 through the arm 10, thence to the armature A through conductor 20. The switch 9 being now free as shown in dotted lines the field current passes from the pivot 7 and arm 6 to the studs 3, 50 and back to line through conductor 21. By now moving the arm 6 to the left the resistance 5 will be inserted in the field circuit and the motor speeded up. Upon failure of voltage the arm 10 will be released and in returning to the off position will carry with it the arm 6.

It will thus be seen that I have provided a simple and convenient arrangement for both starting and regulating the speed of a motor, 60 both operations being performed by a single controlling member, means being also provided for returning said arm to the off position upon the occurrence of abnormal circuit conditions. The controlling arm during the

regulating movement is free to be moved in either direction, and it is only when the arm 10 is released that the controlling arm is placed under spring tension.

While I have in accordance with the patent statutes shown specific means for carrying out my invention, it should be understood that I do not limit my invention to the specific construction or arrangement of circuits herein shown and described since this may be varied by one skilled in the art without departing from the spirit of my invention, the scope of which is set forth in the annexed claims.

What I claim as new and desire to secure by Letters Patent of the United States, is,—

1. A controlling device for electric circuits comprising a pair of resistances provided with contacts, a controlling member simultaneously engaging said contacts, and connections for rendering said member ineffective in controlling one of said resistances when moved in one direction and the other of said resistances when moved in the opposite direction.

2. A motor starting and controlling rheostat comprising an armature resistance and a field resistance each provided with contacts, a controlling member simultaneously engaging said contacts, and connections for rendering said member ineffective to control one of said resistances when moved in one direction and the other of said resistances when moved in the opposite direction.

3. A motor starting and controlling rheostat comprising an armature resistance and a field resistance each provided with contacts, a controlling member simultaneously engaging said contacts, and connections whereby said member is movable in one direction to control the starting resistance and in the opposite direction to control the field resistance.

4. A motor starting and controlling rheostat comprising an armature resistance and a field resistance each provided with contacts, a controlling member simultaneously engaging said contacts, and connections whereby said member is movable in one direction to cut out starting resistance and in the opposite direction to cut in field resistance.

5. A controlling device for electric circuits comprising a plurality of resistances provided with contacts, a controlling member simultaneously engaging said contacts, means for short-circuiting one of said resistances as the element is moved in one direction, and means for short-circuiting another of said resistances as the element is moved in the opposite direction.

6. A controlling device for electric circuits comprising a pair of resistances, a controlling member therefor, means for short-circuiting one of said resistances as the element is moved in one direction, and means for open-

ing said short-circuit and simultaneously short-circuiting the other resistance when the element reaches a predetermined position.

7. A controlling device for electric circuits comprising an armature resistance and a field resistance, a single controlling arm therefor, connections whereby the armature resistance is short-circuited as the arm is moved in one direction and the field resistance short-circuited as it is moved in the opposite direction, and means for returning the arm to the off position upon failure of voltage.

8. A controlling device for electric motors comprising a pair of resistances, a controlling member therefor, connections for rendering said member ineffective in controlling one of said resistances when moved in one direction and the other of said resistances when moved in the opposite direction, and means for automatically placing the resistances in a protective position with reference to the motor.

9. A motor starting and controlling rheostat comprising an armature resistance and a field resistance, a controlling member therefor, connections whereby said member is movable in one direction to control the starting resistance and in the opposite direction to control the field resistance, and means for automatically moving said member from the control of said resistances upon the occurrence of abnormal circuit conditions.

10. A motor starting and controlling rheostat comprising an armature resistance and a field resistance, a controlling member therefor, connections whereby said member is movable in one direction to cut out starting resistance and in the opposite direction to cut in field resistance, and means for automatically returning said member to the off position upon the occurrence of abnormal circuit conditions.

11. A controlling device for electric circuits comprising a pair of resistances having contacts arranged in parallel rows, a controlling member movable over said contacts and simultaneously engaging the same, and connections whereby said element is ineffective to control one of said resistances as it is moved to a predetermined position in one direction and ineffective to control the other resistance when brought back by a return movement.

12. A controlling device for electric circuits comprising a pair of resistances having contacts arranged in concentric rows, a pivoted controlling member movable over said contacts and simultaneously engaging the

same, and connections whereby said element is ineffective to control one of said resistances as it is moved to a predetermined position in one direction and ineffective to control the other resistance when brought back by a return movement.

13. A controlling device for electric circuits comprising resistance contacts arranged in concentric rows, a pivoted controlling arm movable over said contacts and simultaneously engaging the same, and connections whereby one of said rows is short circuited when the arm is moved to a predetermined position in one direction and another of said rows short circuited during the return movement.

14. A controlling device for electric circuits comprising resistance contacts arranged in concentric rows, a pivoted controlling arm movable over said contacts and simultaneously engaging the same, connections whereby one of said rows is short circuited when the arm is moved to a predetermined position in one direction and another of said rows short circuited during the return movement, and means for moving said arm out of engagement with said contacts upon the failure of voltage.

15. A motor starting and controlling rheostat comprising an armature resistance and a field resistance, a controlling member therefor, connections whereby said member is movable in one direction to control the starting resistance and in the opposite direction to control the field resistance, means for returning said member to the off position, and means for rendering said returning means inoperative after running conditions have been established until the occurrence of abnormal circuit conditions.

16. A motor starting and controlling rheostat comprising an armature resistance and a field resistance, a pivoted controlling arm therefor, connections whereby said member is movable in one direction to cut out starting resistance and in the opposite direction to cut in field resistance, a spring for returning said arm to the off position, and a no-voltage magnet for rendering said spring ineffective to return the arm when the latter has been moved to running position.

In witness whereof, I have hereunto set my hand this 12th day of January, 1907.

FRANK J. SEABOLT.
